UNITED STATES PATENT OFFICE.

THEOBALD OBACH, OF VIENNA, AUSTRIA-HUNGARY.

CABLE-GRIPPING MECHANISM.

SPECIFICATION forming part of Letters Patent No. 423,803, dated March 18, 1890.

Application filed July 9, 1887. Serial No. 243,904. (No model.) Patented in Belgium May 9, 1887, No. 77,384; in France May 11, 1887, No. 183,488; in England May 11, 1887, No. 6,925, and in Italy September 6, 1887, No. 21,705.

To all whom it may concern:

Be it known that I, THEOBALD OBACH, a citizen of Switzerland, and a resident of the city of Vienna, in the Empire of Austria-Hungary, 5 have invented certain new and useful Improvements in Cable-Gripping Mechanism, (for which I have obtained Letters Patent as follows: in France May 11, 1887, No. 183,488; in Belgium May 9, 1887, No. 77,384; in England 10 May 11, 1887, No. 6,925, and in Italy September 6, 1887, No. 21,705,) of which the following is a specification.

My invention has relation to gripping or clamping mechanism for the wires or cables 15 of wire-rope ways or other cable conveyers; and it consists in the novel construction and combination of parts hereinafter described and specifically claimed.

In the drawings, Figure 1 is a vertical central section, and Fig. 2 a vertical transverse section, of a grip embodying my invention; and Fig. 3, a plan view.

The clamping or gripping apparatus embraces a stationary jaw and a movable or adjustable jaw, which is opened and closed by means of a knee-lever.

The gripping mechanism comprises the casing G, having the clamping-jaw k cast thereon. The movable jaw k' is suspended in the casing 30 by a bolt b'. The knee-lever is formed by the links s and s', which turn upon the bolt b², and by the prop m n o, that turns upon the bolt b³ and upon the bolt b⁴, in combination with the movable jaw k'. The handle l serves to move 35 the clamping apparatus, the same being moved upward or downward. During the downward motion the angle which is formed by the three pivots b² b⁴ b³ of the knee-lever system be-

comes larger and larger until the three points are in a straight line and the pressure has 40 accordingly reached its maximum. On the handle l being turned upward it turns upon the bolt b³ and presses upon the pawl p, which engages with the ratchet-disk Z, that is cast upon the movable jaw k'. 45

The apparatus, as soon as it is clamped, is fixed by the pawl p, so that it cannot open of itself. The spring f, which is clamped between the front wall of the casing and the movable jaw, has for its object to prevent the 50 handle and the knee-lever from descending, if the apparatus is once opened, in order that the apparatus shall not close accidentally. The two jaws k and k' are provided with rollers R for centering the drawing-rope, as in 55 the above-described clamping apparatus. The jaws are, moreover, lined for purposes of easy repair necessitated by wear and tear.

The gripping mechanism for practical use is secured to the truck or object to be conveyed 60 by having the casing G bolted to such vehicle, as adequately shown in Fig. 1.

What I claim is—

In a clamping or gripping device for wire-rope ways, the combination, with the casing G, 65 having the jaw k and a pivotally-suspended jaw k', of the knee-levers or toggles comprising the links s s', the handle l, bolts b² b³ b⁴, prop m n o, and the locked disk Z and pawl p, substantially as described. 70

In testimony whereof I have affixed my signature in presence of two witnesses.

TH. OBACH.

Witnesses:

JOHN A. LISSNER,
E. G. F. MOELLER.
